UNITED STATES PATENT OFFICE

JESSIE C. TAINTOR, OF WICHITA, KANSAS

DESIGN FOR TONGS

Application filed May 18, 1931. Serial No. 39,880. Term of patent 3½ years.

To all whom it may concern:

Be it known that JESSIE C. TAINTOR, a citizen of the United States, residing at Wichita, in the county of Sedgwick and State of Kansas, has invented a new, original, and ornamental Design for Tongs, of which the following is a specification.

Referring to the drawings:

Fig. 1 is a side view of one of the tongs.

Fig. 2 is a transverse view of Fig. 1 showing the spread of the tongs.

The said views show my new, original, and ornamental design.

I claim:

The ornamental design for tongs, as shown.

In testimony whereof I affix my signature.

JESSIE C. TAINTOR.
